UNITED STATES PATENT OFFICE.

EBEN WILMER LONG, OF CHICAGO, ILLINOIS.

REGULATING-VALVE FOR TANKS.

SPECIFICATION forming part of Letters Patent No. 529,739, dated November 27, 1894.

Application filed July 16, 1894. Serial No. 517,672. (No model.)

To all whom it may concern:

Be it known that I, EBEN WILMER LONG, a citizen of the United States, and a resident of Chicago, Cook county, Illinois, have invented 5 certain new and useful Improvements in Regulating-Valves for Return-Tanks, of which the following is a full, clear, and exact description, reference being had to the accompanying drawings, and to the letters and figures of 10 reference marked thereon.

The object of my invention is to provide a valve for regulating the supply of water to a tank automatically, and so that, when the water in the tank reaches a given point the water will drain therefrom, and when below that point the water will enter the same, substantially as hereinafter fully described, and as illustrated in the drawings, in which—

Figure 1 is a side elevation of my invention 20 showing a portion of a return tank to which it is applied. Fig. 2 shows a side elevation of the same on a slightly enlarged scale. Fig. 3 is a longitudinal vertical central section of the valve. Fig. 4 is a detail view of the upper end portion of the valve-spindle of the 25 exhaust valve of my invention, and Fig. 5 is a detail view of the block against which the float lever bears.

In the drawings A represents a suitable tank 30 having a supply pipe a, the end of which entering said tank is, preferably, provided with lateral arms, each of which has a longitudinally arranged series of perforations through which the water issues into the tank, or out 35 through which the excess water drains, as will hereinafter more fully appear. The height to which the water rises in the tank is regulated by means of a suitable float B, through the medium of my improved regulating valve to 40 which said float is connected by an arm, substantially as shown.

One end of my improved regulating valve is fastened in and to the head of the tank, preferably, on a plane indicating the low water mark in the tank at which it would be desirable to open said valve so as to increase the supply of water in the tank. The casing in which the operative parts of my invention are housed, is made in three parts, namely: 45 an inner portion C, an outer portion E and an intermediate portion D. The inner end of the portion C is made cylindrical, and is,

preferably, screw threaded as far as the circumferential flange c. This screw threaded part is passed through a suitable opening in 55 the head of the tank until stopped by said flange c, whereupon a nut b is screwed over said end to clamp the casing of the valve in place. I prefer to interpose a suitable packing ring b' between said nut and the portion 60 of the tank it would otherwise come in contact with, so as to make a perfectly water tight joint.

The intermediate portion D of the casing has its inner part, preferably, globe shaped 65 and has its inner extremity provided with a tapped opening, into which the screw threaded outer end of said portion C is screwed until the circumferential flange c' bears tightly against the said intermediate portion D. This 70 globe-shaped inner part of the portion D is provided with a vertically projecting inlet stub a, to which the main supply pipe d is coupled, and diametrically opposite this stub a' is a handhole which is normally closed by 75 the cover e. The waist of this intermediate portion D is less in diameter than the remainder of its length so as to provide a valve-seat f against which the inlet valve G normally presses. The outer part of this intermediate portion D is provided with a downwardly projecting stub D' to which the outer end of the tank supply pipe a is connected. The outer portion E of the casing of the valve 80 is shaped so as to form practically a pipe 85 angle, the inner flanged end edges of which are suitably secured to the correspondingly shaped outer end edges of the intermediate portion D. The outer end or discharge end of the portion E is, preferably, also screw threaded so as to be coupled to the pipe E' leading to a drain or sewer. Just inside the plane of the downwardly extending discharge end of the portion E, it is provided with a suitable partition in which is a contracted 90 opening, the inner annular edges of which are shaped as shown to provide a seat i for the discharge valve H.

Valve H is made of any suitable material, and is securely fastened to the outer end of 95 the horizontal spindle K, the outer end portion of which is provided with a circumferential flange 2 which bears outward against said valve H, and between which and a nut h

said valve is secured. The outer extremity of this spindle K is smooth and extends through and moves in a suitable guide-opening in a bridge spanning the outer end of the contracted opening normally closed by valve H. The part of the spindle K between the flange 2 and the tank, is of the same diameter, and extends centrally through the casing, to and through the valve G and the hollow stem L to the outer end of which said inner valve G is secured. This hollow stem L is provided with a circumferential flange near its outer end against which the valve G is placed and secured by means of a nut m; a washer n being, preferably, placed between the said valve G and nut m to prevent abrasion of the valve.

The valves G and H are normally kept in their relative positions against their respective seats, by means of the expansion coil 20 spring R, interposed between them and surrounding the spindle K, and having its ends pressing against said valves in opposite directions, as shown in the drawings.

The inner ends of both the stem L and the 25 spindle K extend into the tank beyond the inner extremity of the casing of the valve, and the spindle K extends a suitable distance farther into the tank than the end of the hollow stem through which it passes. Now the 30 obvious object is to draw valve H away from its seat when the water in the tank is too high, so as to drain the surplus water therefrom into the sewer; and its object is likewise to push the valve G away from its seat, when 35 the water in the tank is low, so as to supply additional water to the tank as needed. To accomplish this result I provide an L-shaped lever N, which is fulcrumed in the arms r projecting upward from a collar O screwed onto 40 the inner screw-threaded end of the casing inside the tank. The vertical arm of this lever extends downward from its fulcrum into a longitudinal slot k intersecting the inner end of the spindle K diametrically and extending from its inner extremity to a point 45 inside of the inner end of the stem L, as shown. I place on both sides of the vertical arm of lever N I-shaped blocks 9 and 10, respectively, the longitudinal webs of said blocks 50 resting in the slots, and the heads thereof coming outside and bearing against the circumference of the spindle. The block 9 is secured in place by the lock-nuts 7 and 8, and the block 10 normally rests against the inner 55 annular edges of the stem L. One of the peculiarities of this construction is that it enables the float in the tank to be given a limited movement without affecting the valve, thus enabling me to provide for a high water 60 and low water danger mark between which the float may move without causing the water to enter the tank or discharge therefrom. Now the inner end of the horizontal arm of the lever N is suitably secured to the opposite 65 site end of the arm attached to the float B, and according as this arm moves, the lever N is operated so that its vertical arm will bear

outward against the stem L to open the valve G and thereby increase the supply of water to the tank, or will draw the valve H inward 70 through the medium of the spindle K so as to exhaust the surplus water from the tank into the sewer.

What I claim as new is—

1. The combination with a water tank, and a pipe discharging into the same, of a suitable float on the end of an arm, a lever to which said arm is connected, a valve closing the inlet leading to the pipe which discharges into said tank, and a valve closing a drain outlet out through which the backrush of water from the tank can drain, said inlet valve being above the drain valve and having a hollow stem arising therefrom, and said drain valve having a vertical spindle arising therefrom to and above the hollow stem of the inlet valve, said valves moving in opposite directions when closing and moved toward each other according to the movement of said lever in order to open.

2. The combination with a tank, and a pipe discharging into the same, of a float, a lever to which the said float is connected by a suitable arm, a valve G closing the inlet to said pipe, a sleeve stem arising therefrom, a valve 95 H closing said drain pipe, a spindle arising therefrom and passing through said sleeve stem and an expansion spring placed between and bearing against said valves, and a suitable hollow casting having an inlet above valve G, a drain outlet below valve H and an outlet between said valves which connects with the pipe discharging into the tank; said lever depressing valve G when the water in the tank is low, and raising valve H when 105 the water in the tank is too high, as set forth.

3. The combination with a tank, and an inlet pipe or supply pipe, of a float, an arm depending therefrom, an L-shaped lever to which the said arm is connected, a valve G closing the inlet passage a sleeve arising therefrom, a valve H closing a drain outlet, a spindle arising therefrom which passes through and to a point above the said stem and having its upper end slit longitudinally and nut 115 screwed onto the upper end of the same, an expansion spring placed between and pressing in opposite directions against said valves, and a suitable vertical hollow casting within which said valves are housed having a lateral inlet above the valve G, a lateral outlet connected to the supply leading to and discharging into the tank coming between said valves, and a drain outlet below valve H, said lever being L-shaped and having its horizontal arm entering the slit in the upper end of the spindle and lifting said spindle when said lever is moved in one direction and depressing said sleeve stem when moved in the opposite direction.

EBEN WILMER LONG.
